UNITED STATES PATENT OFFICE.

GEORGE W. BAKER, OF RHEEMS, PENNSYLVANIA.

DESIGN FOR A BADGE.

50,803.

Specification for Design.

Patented May 22, 1917.

Application filed November 2, 1916. Serial No. 129,242. Term of patent 7 years.

To all whom it may concern:

Be it known that I, GEORGE W. BAKER, a citizen of the United States, residing at Rheeems, in the county of Lancaster and State of Pennsylvania, have invented a new, original, and ornamental Design for a Badge, of which the following is a specification, reference being had to the accompanying drawing, forming part thereof.

The figure is a face view of a badge, showing my new design.

I claim:—

The ornamental design for a badge, as shown.

GEORGE W. BAKER.

Witnesses:

EDWARD V. SMITH,
JOHN H. WOOD.
